DRAIN CONTROL MEANS

Filed Dec. 5, 1933

UNITED STATES PATENT OFFICE

1,990,689

DRAIN CONTROL MEANS

Benjamin Grismer, Bowdle, S. Dak.

Application December 5, 1933, Serial No. 701,067

1 Claim. (Cl. 137—34)

This invention relates to drain control means for the suction pipe or line of a pump, and it is an object of the invention to provide a means of this kind which can be readily applied to and effectively employed with a suction pipe or line of a size for insertion within a casing of a diameter of three inches or more.

It is also an object of the invention to provide a means of this kind which includes a sliding valve member for coaction with a drain opening or vent provided through the wall of the suction pipe or line at a point below the freezing point, the movement of the valve member in opposite directions being limited to assure said member at all times overlying the drain opening or vent so that said member provides an effective medium to prevent the water as it drains out through the opening or vent being discharged upon or squirting against the well casing and washing off rust on the casing down into the water thus not only eliminating such contamination of the water but materially prolonging the life of the well casing.

Another object of the invention is to provide a means for controlling the discharge through a drain opening or vent provided in the wall of a suction pipe or line for a pump including a sliding valve member for said pump which is moved downwardly when it is desired to open the flow out through the drain opening or vent and wherein in said valve member carries a facing of leather or kindred material which constitutes the valve member for closing the drain opening or vent when the valve member is moved upwardly, the downward movement of the valve member to open the drain opening or vent positioning the facing below the opening so that the water as discharged through the drain opening or vent will wash down over the facing and thus prevent the same from drying out and in the course of time becoming defective as such moistening of the facing will maintain the same wet and soft so that it will have proper coaction with the pipe or line.

The invention consists in the details of construction and in the combination and arrangement of the several parts of my improved drain control means for the suction pipe or line of a pump whereby certain important advantages are attained and the device rendered simpler, less expensive and otherwise more convenient and advantageous for use, as will be hereinafter more fully set forth.

The novel features of my invention will hereinafter be definitely claimed.

In order that my invention may be the better understood, I will now proceed to describe the same with reference to the accompanying drawing, wherein:—

Figure 1 is a fragmentary view partly in section and partly in elevation and of somewhat a

diagrammatic character illustrating a drain control means constructed in accordance with an embodiment of my invention and in applied position;

Figure 2 is a fragmentary elevational view of the parts of the means as comprised in the lower portion of Figure 1;

Figure 3 is an enlarged fragmentary view in section taken lengthwise of the suction pipe or line with the valve member in the position illustrated in Figure 1;

Figure 4 is a view similar to Figure 3 showing the valve member in its lowered position to open the drain opening or vent in the suction pipe or line;

Figure 5 is a transverse sectional view taken substantially on the line 5—5 of Figure 4 looking in the direction of the arrows;

Figure 6 is a fragmentary view partly in section and partly in elevation illustrating in detail the means herein employed for mounting the pipe protector.

As disclosed in the accompanying drawing, P denotes a conventional type of pump mounted upon a wall head H and which pump has depending therefrom a suction pipe or line L adapted to extend a required distance within a well opening and more particularly within a well casing (not shown). The line L at a desired distance below the pump P is provided in its wall with a drain opening or vent 1. This opening or vent 1 is positioned a distance below the pump P sufficient to be arranged below the freezing point and is, of course, provided to allow water within the line L within the freezing zone to readily drain out.

The foregoing features referred to are well known and form no part of the present invention.

My improved means for controlling the flow through the opening or vent 1, as herein disclosed, comprises two elongated guide strips 2 adapted to be arranged in parallelism upon the pipe or line L at opposite sides of the opening or vent 1. Riveted, as at 3, or otherwise attached to the inner faces of the strips 2 are the laminations 4 of leather or kindred material which have direct contact with the periphery of the pipe or line L. These rivets 3 also hold to the strips 2 the transversely disposed bands 5. Each of these bands 5 bridges the space between the strips 2 and has its extremities extended beyond the outer longitudinal margins thereof to provide straps 6 extending along opposite sides of the pipe or line L. These strips 6 are of a length sufficient to permit a clamping screw 7 to be engaged therethrough as particularly illustrated in Figure 5 so that the nut 8 can be employed to effect the desired clamping of the members 2 upon the pipe or line L.

Each of the straps 6 at a desired point thereon is provided with an opening 9 adapted to register

with an opening 10 provided in the wall of the pipe or line L so that a screw 11 may be employed for further holding the strips 2 in applied position.

5 The screws 11 are preferably employed when the pipe or line L is of a size to be inserted within a casing approximately three inches in diameter and when so used and if necessary, after the screws 11 have been applied the bolt 7 may be 10 removed and the extended ends of the straps 6 bent as by hammer blows to lie close adjacent the periphery of the pipe or line L.

Freely slideable between the strips 2 is an 15 elongated valve member M which passes between the pipe or line L and the portions of the bands 5 bridging the space between the strips 2 and riveted, as at 12, or otherwise carried by the member M at a point between the bands 5 is a stop block or part 14 which is adapted to contact with the bands 5 whereby the extent of endwise movement of the member M in either direction is positively limited.

20 The inner face of the valve member M at the lower end portion thereof has riveted, as at 15, or otherwise secured thereto a facing 16 of leather or kindred material and which constitutes a valve having direct contact with the periphery of the pipe or line L and which facing or valve 16 when the member M is in its raised or lifted position 25 closes the drain opening or vent 1. The upper portion of this facing 16, as indicated by broken lines at 17 in Figure 2, is gradually reduced in width and as illustrated in Figures 3 and 4 this upper restricted end portion of the facing 16 is 30 beveled upwardly and outwardly toward the member M, as indicated at 18. This restricted portion 17 of the facing 16 together with the bevel 18, when the member M is in its lower position, assure the desired opening of the vent 1 35 with the desired discharge of the water therethrough from within the pipe or line L.

40 As is illustrated in the accompanying drawing, the lower band 5 is so positioned upon the pipe or line L to limit further downward movement of the member M shortly after the lamination 16 has been shifted substantially entirely 45 below the drain opening or vent 1. With the member M in open position as illustrated in Figure 4, the water as it discharges through the opening or vent 1 will contact with the overlying portion of the member M and thus be prevented from squirting upon the well casing and carrying down into the water rust which may 50 have accumulated on the inner surface of the casing. A continued action of this kind within a reasonable time would result in a material deterioration of the casing aside from a pollution 55 of the water. Therefore, my improved control means materially prolongs the life of the well casing.

60 It is also to be particularly noted that when the drain opening or vent 1 is open for discharge therethrough, the member M is in a position to arrange the facing 16 below said opening or vent 65 1 so that the water as it discharges through such opening or vent 1 will effectively wash over the facing 16 and thereby maintain the same moist and soft so that it will be in the best possible condition for effective use and not allowed to dry out. The discharge of the water through the 70 opening or vent 1 is further facilitated by the

restricted portion 17 and bevel 18 at the upper part of the facing 16.

An elongated operating member 19 is secured at its lower end to the upper portion of the member M and this operating member 19 is of a length to extend a desired distance above the well head so that a person upon the ground level may readily adjust as desired the member M into open or closed position with respect to the drain opening or vent 1.

10 This operating member 19 as herein disclosed is directed through an elongated pipe or tubular member 20 which protects the major portion of said member 19 above the head H or above the ground surface from being in any way retarded in operation by freezing. The lower portion of this member or pipe 20 as herein disclosed is directed through a suitably positioned opening in the base flange 21 of the pump P and has threaded thereon above and below said flange 20 20 21 the holding nuts 22. Positioned between the uppermost nut 22 and the flange 21 is a washer 23 of rubber or similar material and interposed between this washer 23 and the uppermost nut 22 is a metallic washer 24. The nuts 22 and the parts associated therewith provide an effective means for maintaining the pipe or tubular member 21 in working position.

25 From the foregoing description it is thought to be obvious that a drain control means constructed in accordance with my invention is particularly well adapted for use by reason of the convenience and facility with which it may be assembled and operated, and it will also be obvious that my invention is susceptible of some 30 change and modification without departing from the principles and spirit thereof and for this reason I do not wish to be understood as limiting myself to the precise arrangement and formation of the several parts herein shown in carrying out my invention in practice except as 35 hereinafter claimed.

40 I claim:—

45 In combination with the suction pipe line of a pump, the wall of which has a drain opening, 45 elongated strips disposed lengthwise along the pipe line at opposite sides of the drain opening, bands secured to said strips and bridging the space therebetween, means associated with said bands for holding the strips to the pipe line, an 50 elongated valve member engaged between the strips for sliding movement lengthwise of the pipe line, said valve member being held in place by the portions of the bands bridging the space 55 between the strips, a stop member carried by the 55 valve member between the bands for contact with the bands to limit the movement of the valve member in opposite directions, and a leather facing carried by the inner face of the valve member, said leather facing closing the 60 valve opening when the valve member is raised, said leather facing being entirely below the drain opening when the valve member is in its lowermost position, the portion of the valve member immediately adjacent to the leather facing serving to direct the water passing out through the drain opening upon the leather facing, the upper end portion of the facing being beveled, said bevel facilitating draining of the pipe line when the valve member is in its lowered open position. 70

BENJAMIN GRISMER.
